UNITED STATES PATENT OFFICE.

WILLIAM M. GORRY, OF WILLIMANTIC, CONNECTICUT.

PLOW.

SPECIFICATION forming part of Letters Patent No. 318,930, dated June 2 1885.

Application filed October 23, 1884. (No model.)

To all whom it may concern:

Be it known that I, WILLIAM M. GORRY, of Willimantic, in the county of Windham and State of Connecticut, have invented certain new and useful Improvements in Plows, which improvements are fully set forth and described in the following specification, reference being had to the accompanying drawings.

10 This invention relates to the construction of plows, it being my purpose to improve materially the form of the mold-board, point, and landside, with a view to producing a plow which will require less power to draw it, and 15 which shall be under the easy control of the operator in charge.

Said invention consists, first, of an improved form of mold-board; second, of extending the point-section a considerable distance above and below the mold-board, to which it is attached, and also of so constructing and hanging said point-section that it presents an actual cutting edge (chisel-like) of such shape that continual friction and abrasion tend to keep it sharp rather than to dull said point; third, of gradually concaving longitudinally the lower outer side of the landside; and, fourth, of so cutting away the rear end of the mold-board and landside that 30 the complete plow is practically balanced, making the heel of the landside and of the point-section the fulcrum on which the plow may be swung, as more fully described hereinafter.

35 In the annexed drawings, Figure 1 is a side view of my plow complete. Fig. 2 is a view of the mold-board and point-section from the rear side, the landside being outlined with dotted lines. Fig. 3 is a front-end view of 40 said plow with beam removed. Fig. 4 is a cross-section on line xx of Fig. 3, showing the cutting-edge of the point-section.

The letter A represents my mold-board, having a standard, a , by which it is attached 45 to the beam B. The mold-board A extends rearward a considerable distance, and is concaved throughout its entire length. At the forward end of said mold-board is an extension (indicated by dotted lines in Fig. 1) of 50 the same general shape as the point-section C, forming an inner supporting-shell for said point-section. This forward extension is set

back or below the face of the mold-board proper, so that when the point-section is in place and properly secured to the mold-board 55 the concaved outer side of said point matches perfectly the concaved surface of the mold-board. I find by thus supporting the point by a shell of the same shape and of nearly the same size there is less liability to break or to 60 work loose than when bolted to a single lug or boss on the mold-board. The point-section C extends forward with the usual form of "duck-bill," b , and upward above the mold-board, forming a shoe, c . The form of the 65 point-section on the landside side forms one of the features of my invention. So far as I am acquainted with the state of the art the point-sections in common use are formed either wedge shape or with one of their sides parallel with the line of movement of the plow. In such cases the dirt and gravel as they are cut and turned up are constantly abrading and 70 wearing the cutting-edge of the point and soon dull it. To avoid this result, and to 75 make a point whose cutting-edge will be sharpened instead of dulled by use, I have cut the landside side of my point-section under, as shown in Fig. 4. It will readily be seen that the wear in such a form will be always on the 80 mold-board side, and that as the iron wears back the cutting-edge is automatically sharpened. The landside E, which is secured to a ledge, d , (formed as an integral part of the mold-board,) is so shaped at its front end that 85 it matches the vertical cut-under wall of the point-section, but as it extends rearward is formed with a continually increasing concaved outer surface, so that at the heel it is considerably hollowed, as shown in Fig. 3. 90 By thus concaving said landside its base is extended outward and tends to cut under and loosen the material plowed, requiring less power to move the plow than if it were formed to push the dirt (as many plows in common 95 use do) instead of cutting under and loosening it.

Another and the final improved feature of my plow consists in making the heel of the landside correspond in length with the heel of 100 the point-section on the opposite side, so that the plow when in use is balanced or substantially balanced on said heels of the point-section and landside. It has been the more

common custom heretofore to allow either the landside or mold-board to extend well rearward, and when it is desired to bear down on the handles and throw the point out of the ground an extraordinary weight must be applied to the handles to accomplish the desired result.

In my new form of plow the overhanging portions of both the mold-board and landside reach rearward to carry and deposit the earth plowed, but, being elevated, do not offer any resistance when it becomes necessary to elevate or depress the point.

Having thus described my invention, I claim—

1. In combination with the mold-board having the beam-standard *a*, ledge *d*, and point-supporting shell all cast integral with each other, the point *C*, extending above the point of junction with the mold-board, and having its landside face cut back, forming an

acute angle with the line of movement of the complete plow, and a landside whose outer lower side (beginning at the point end) is formed with a gradually-increasing concavity, all as and for the purpose specified.

2. In a plow, a point-section whose landside face is cut back, forming an acute angle with the line of movement of the plow, a mold-board, substantially as described, and a landside whose outer lower side is gradually concaved from the point rearward, said landside being so cut away at its rear end that its heel is opposite the heel of the point, the complete plow being balanced on said heels, all of said elements being combined and used as and for the purpose specified.

WILLIAM M. GORRY.
